UNITED STATES PATENT OFFICE.

ARTHUR CHEETHAM, OF TORONTO, ONTARIO, CANADA, ASSIGNOR OF ONE-HALF TO
FRED M. BAWDEN, OF TORONTO, ONTARIO, CANADA.

SHEET-CUTTING MACHINE.

Application filed November 5, 1920. Serial No. 421,926.

To all whom it may concern:

Be it known that I, ARTHUR CHEETHAM, of the city of Toronto, in the county of York, in the Province of Ontario, in the 5 Dominion of Canada, have invented certain new and useful Improvements in Sheet-Cutting Machines, and do hereby declare that the following is a full, clear, and exact description of the same.

10 This invention has reference to the cutting or notching, more particularly in a marginal manner of moving sheets such for example as of paper or linen, and has for its objects to enable such sheets to be cut or 15 notched whilst in motion without tearing and in a very precise manner, so that notches having a width proportionately smaller to their depth may be accurately cut in moving sheets, and has as a further object to 20 provide for such purpose a rotary punch which will during a stage of its operation follow a moving sheet at practically an equal speed thereto and effect the cutting or notching thereof during such stage.

25 A still further object is to provide a self-stripping punch wherein the portion cut from the sheet is removed and the punch withdrawn from the path of the sheet in a rapid and practically instantaneous manner, 30 whereby tearing or distortion of the sheet is avoided; and a still further object is to provide means whereby a sheet having lineal movement may be cut or notched by a punch having a rotary movement and to provide 35 means whereby said punch in its rotation is brought into and out of operable juxtaposition with the moving sheet.

Still further objects subsidiary to or resulting from the aforesaid object or from the 40 construction or operation of the invention as it may be carried into effect will become apparent as the said invention is hereinafter further disclosed.

In carrying the said invention into effect 45 I may provide, in a sheet cutting machine, means for the cutting or notching of a moving sheet such as a notched member contiguous which the margin of the sheet travels and a punch complementary to said notch, 50 which punch may be carried by the said member and adapted to be carried into and out of juxtaposition with the margin of said sheet, said punch practically agreeing in speed and direction with the movement of said sheet when juxtaposed therewith, and

means effecting the cutting operation of said punch such as a cam device adapted to bring said punch into cutting position and punch actuating means adapted to effect the cutting operation of said punch, which punch is arranged to be immediately withdrawn from the path of said sheet when said cutting operation is effected; all of which is more particularly described and ascertained by way of example having reference to the construction illustrated in the accompanying drawings, wherein:

Figure 1 is a fragmentary plan view of a sheet cutting machine embodying my invention.

Figure 2 is a transverse section of the same taken on the line 2^x—2^x, Figure 1.

Figure 3 is a longitudinal vertical section taken on the line 3^x—3^x, Figure 1 the feed roller being omitted.

Figure 4 is a perspective view of one of the rotary punch devices in operation.

Figure 5 is a detail view of one of the said rotary punch devices and

Figure 6 is a detail fragmentary view of 80 a sheet punched by the device illustrated.

Similar characters of reference indicate similar parts in the several Figures of the drawing, and Figures 4 and 5 are drawn to a larger scale than are Figures 1, 2 and 3.

1 are side frames of a machine with which the invention is illustrated, 2 being a feed shaft upon which a feed roller 3 is mounted and coacts with an idler roller 4 to feed a sheet 5, of linen or paper, or other desired material; the mechanism to be described in this instance being illustrated as arranged for the purposes of cutting upwardly turned margins 6 of such sheet.

Mounted on the said shaft 2 and facing 95 one another, in spaced relation according to the width of the said sheet are rotary punch devices each comprising a drum 7 having a disc or face plate 8 rotatable therewith over which the respective margins 6 of the sheet 100 5 travel as the said sheet 5 is fed forwardly by the feed roller 3. The said face plates 8 are provided with orifices, or notches, 9 and 10, in which punches 11 and 12 complementary thereto may slide, the said punches being illustrated as having reduced stems, 13 and 14 respectively of smaller cross sectional dimensions than the said punches 11 and 12 the said stems 13 and 14 connecting the said punches operatively with blocks 15 and 16 110

having rearwardly extending tappets 17 and 18 and slidably in grooves 19 in the said drum 7.

The said punch carriers revolve with the shaft 2 at the same speed as the feed roller 3 and the punches being so arranged that their cutting parts are approximately the same distance from the centre of rotation as is the periphery of the roller 3 it follows that 5 such punches will successively be brought into and out of juxtaposition with the margin of the sheet 5, as it is fed forwardly and when so brought into juxtaposition will be travelling in approximately the same direction and at the same speed as the said sheet.

It will be seen that the cutters 11 and 12 are arranged to effect their cutting operation by extending outwardly over the margins of 20 the sheet in spaced relation to the face plates 8 and thereafter being retracted through the said margins of the sheet into the notches or orifices 9 and 10 of the face plates 8 and, to effect this operation, stationary cams 20 25 are arranged in the paths of the said tappets 17 and 18 the apices of the said cams being at the lowermost point in the rotary path of the tappets whereby the said cams will through the said tappets, blocks and 30 stems effect the gradual movement of the said punches with respect to the said face plates 8 in order that the said punches 11 and 12 will be spaced therefrom prior to 35 their being rotated into juxtaposition with the margins of the sheet.

21 and 22 are springs compressively situated between the blocks 15 and 16 respectively and the plate 8 whereby the tappets 17 and 18 are forced rearwardly against the 40 cams 20.

As each punch 11 or 12 in turn is brought into spaced relation with the face of the disc 8 and is rotated until it passes over the margin of the sheet, as described, its respective 45 tappet 17 or 18 reaches the apex of its operating cam 20 which effects the said spacing of the punch with respect to the face plate or disc, so that the further rotation of the punch carrier results in the said tappet 17 or 50 18 passing over the said apex of the cam allowing the springs 21 or 22, as the case may be to effect through the medium of the respective block and stem the rapid retraction of the punch 11 or 12 through the sheet and 55 into the orifice, or notch in the said plate carrying with it the piece of the sheet which has been cut and passing completely out of the path of the moving sheet. This action being almost instantaneous, and occurring at 60 a moment when the said sheet and punch 11 or 12 are travelling in practically the same direction and at the same speed insures a cutting of the sheet true to the configuration of the punch and without tearing or 65 distortion of the said sheet.

The punches carried by the punch carrier may be varied as to number or relative position according to the pattern or frequency of cutting desired, and I have illustrated the punches in this embodiment of my invention as being arranged for the notching of a blank strip for the making of envelopes; Figure 6 illustrating such a strip having the notches cut therein, from which it will be seen that the notches 23 cut by the punches 70 11 are quite narrow in proportion to their depth notwithstanding the cutting thereof as the sheet is travelling at high speed. In this illustration the margins are shown as being laid out in the same plane as the sheet 75 5. 24 indicate notches cut by the punches 12 wherein one of the walls of the notch is practically at right angles to the length of the sheet.

It will be seen that, if the envelope blank 80 be cut, by any suitable means from such a notched sheet such as in the manner indicated in dotted lines thereon, such a blank may be folded on a line extending between the opposite notches 22 whereupon the marginal 85 extensions resulting from the said notching will have their cut ends approximately at right angles to the said margins whereby if such margins be folded and secured to complete an envelope, the corners thereof 90 would be closely interlocked, which, as explained, is rendered possible by the use of the quick-acting, self-stripping punch, brought into juxtaposition with the moving sheet to be punched and operated whilst said sheet 95 and said punch are travelling in approximately the same direction and at approximately the same speed, thus rendering unnecessary any interruption in the progress of the sheet whilst being punched.

100 This invention may be developed within the scope of the following claims without departing from the essential features of the said invention, and it is desired that the specification and drawings be read as being merely illustrative and not in the limiting sense, except as necessitated by the prior art.

110 What I claim as my invention is:

1. In a device of the class described means 115 for the notching of the margin of a moving sheet, said means comprising a notched member over which said margin travels, a punch complementary to the notch in said member rotary means adapted to carry said punch into and out of juxtaposition with the margin of said sheet, said punch practically agreeing in speed and direction of movement with the said sheet when juxtaposed therewith, and means effecting the 120 passage of said punch through said sheet and out of the path of the said sheet during such juxtaposition.

125 2. In a device of the class described, means 130 for the notching of the margin of a moving

sheet, said means comprising a notched member over which said margin travels, a punch complementary to the notch in said member, rotary means adapted to carry said 5 punch into and out of juxtaposition with the margin of said sheet, said punch practically agreeing in speed and direction of movement with the said sheet when juxtaposed therewith, and means effecting the rapid 10 passage of said punch through said sheet and completely into the notch of said member during such juxtaposition.

3. In a device of the class described, means for the notching of the margin of a moving 15 sheet, said means comprising a rotary notched member over which the said margin travels, a punch complementary to the notch in said member and rotating therewith into and out of juxtaposition with the margin of said sheet, said punch practically agreeing in speed and direction of movement with said sheet when juxtaposed therewith, means effecting the movement of said 20 punch outwardly from said member prior to such juxtaposition, and means thereafter effecting the rapid return of said punch through said sheet into the notch of said member.

4. In a device of the class described, means 30 for the notching of the margin of a moving sheet, said means comprising a rotary notched member a punch complementary to the notch in the said member and rotating therewith, means effecting the outward movement of said punch whereby the cutting face thereof is spaced from the surface of said member for the reception of a moving sheet therebetween and means effecting the rapid retraction of said punch into the notch 35 of said member at a predetermined period in the rotation thereof.

5. In a device of the class described, means for the notching of the margin of a moving sheet said means comprising a rotary 45 notched member over which the said margin travels, a punch complementary to the notch in said member and rotating therewith into an out of juxtaposition with the margin of a moving sheet, said punch practically agreeing in speed and direction of movement with said sheet when juxtaposed therewith, means for effecting the gradual outward movement of said punch from the said member prior to such juxtaposition, 55 and means thereafter effecting the rapid return of said punch through said sheet into the notch of said member.

6. In a device of the class described, means 60 for the notching of the margin of a moving sheet, said means comprising a rotary notched member a punch complementary to the notch in said member and rotating therewith means effecting the gradual outward movement of said punch whereby the cutting face thereof is spaced from the surface of

said member for the reception of a moving sheet therebetween and means effecting the rapid retraction of said punch into the notch of said member at a predetermined period in the rotation thereof. 70

7. In a device of the class described, means for the notching of the opposite margins of a moving sheet, said means comprising a pair of punch carriers having synchronized movement and each rotatable in a plane 75 parallel to the surface of the respective margins to be cut, a punch carried and rotated by each of said carriers into and out of juxtaposition with the opposite margins of said sheet and means imparting a reciprocal cutting action to said punches at, right angles to the planes of rotation of said carriers when said punches are so juxtaposed.

8. In a device of the class described, means for the notching of the margins of a moving 80 sheet, said means comprising a rotary disc having a notch therein substantially removed from the axis thereof a punch complementary to the notch in said disc and rotating therewith means effecting the outward movement of said punch, whereby the cutting face thereof is spaced from the surface of said disc for the reception of a moving sheet therebetween, and means effecting the rapid retraction of said punch into 85 said notch at a predetermined period in the rotation of said disc.

9. In a device of the class described, a rotary notched member, a reciprocating punch complementary to said notch and rotating with said member in constant register with said notch, and means alternately reciprocating said punch to a spaced relation with said member and a complete retraction 100 into said notch. 105

10. In a device of the class described, a rotary disc having a notch therein substantially removed from the axis thereof, a reciprocating punch complementary to said notch and rotating with said disc in constant register with said notch, and means alternately reciprocating said punch to a spaced relation with the face of said disc and a complete retraction into said notch. 110

11. In a device of the class described, a rotary punch carrier, a reciprocating punch carried thereby, said punch having its cutting edge presented towards said carrier, and means effecting the cutting operation of said punch as by the movement thereof towards said carrier as it is successively moved by said carrier into a common predetermined position. 115

12. In a device of the class described, a rotary member having a plurality of notches therein, a plurality of reciprocating punches complementary to said notches and rotatable with said member in constant register with said notches, and means effecting the cutting operation of said punches by their entrance 120 125 130

successively into said notches as each of said notches successively assumes a common predetermined position.

13. In a device of the class described, a rotary member having a plurality of notches therein, a plurality of reciprocating punches complementary to said notches and rotatable with said member, said punches having their cutting edges presented towards said member, means effecting the outward movement of said punches successively prior to their approaching a predetermined common position in their rotation, and means effecting the rapid retraction of said punches successively into their respective notches and consequent cutting operation as such predetermined position is assumed.

14. In a device of the class described, a rotary disc having a plurality of notches 20 therein substantially removed from the axis thereof a plurality of punches complementary to the said notches and rotating with said disc and means effecting the cutting op-

eration of said punches by their retraction successively into said notches as each of said punches successively assumes a common predetermined position.

15. In a device of the class described, a rotary disc having a plurality of notches therein substantially removed from the axis thereof, a plurality of punches complementary to the said notches and rotating with said disc means effecting the successive outward movement of said punches whereby the cutting faces thereof are spaced from the surface of said disc prior to said punches assuming a common predetermined position into rotation of said disc and means effecting the rapid retraction of each of said punches as it assumes such predetermined position.

Signed at the city of Toronto, in the county of York, in the Province of Ontario, in the Dominion of Canada, this 17th day of May, 1919.

ARTHUR CHEETHAM.
